Anthony P. DeLio; Thomas E. Ciesco(57) **CLAIM**

I claim the ornamental design for an insulation removal tool, as shown and described.

DESCRIPTION

FIG. 1 is a front perspective view of an insulation removal tool according to my invention;

FIG. 2 is a front elevational view of an insulation removal tool shown in FIG. 1;

FIG. 3 is a back elevational view of the insulation removal tool shown in FIG. 2;

FIG. 4 is a bottom view of the insulation removal tool shown in FIG. 2;

FIG. 5 is a top view of the insulation removal tool shown in FIG. 2;

FIG. 6 is a left side elevational view of the insulation removal tool shown in FIG. 2; and,

FIG. 7 is a right side elevational view of the insulation removal tool shown in FIG. 2.

The broken lines in the drawing are included for the purpose of illustration and form no part of the claimed design.
